UNITED STATES PATENT OFFICE.

LOUIS STEINBERGER, OF BROOKLYN, NEW YORK.

INSULATOR.

1,072,523.

Specification of Letters Patent.

Patented Sept. 9, 1913.

Application filed May 18, 1910. Serial No. 561,964.

To all whom it may concern:

Be it known that I, LOUIS STEINBERGER, a citizen of the United States, and a resident of the city of New York, borough of Brooklyn, in the county of Kings and State of New York, have invented a new and Improved Insulator, of which the following is a full, clear, and exact description.

My invention relates to insulators for general use, my special purpose, however, being to produce an insulator suitable for use upon telephone and telegraph lines, and adapted for promoting accessibility to the wire terminals, and for facilitating the making and breaking of electrical connections more or less permanent, the device thus possessing characteristics that make it adaptable as a wall box.

My invention further comprehends the use of an insulating base in which is mounted a substantially U-shaped metallic member having two portions provided with means for connecting wires with said portions.

My invention relates further to the provision of a suitable covering for the insulating base in order to protect the parts carried by it from the effects of dust and moisture, and enables the covering to be applied to or removed from the base without disturbing the wire connections.

My invention further comprehends the provision of an insulating base provided with means for securing the same to a wall, ceiling or other support, the base being further provided with a plurality of slots disposed on the same face where the conductors are brought into engagement with the substantially U-shaped metallic connectors, and is further provided with means for receiving and securely retaining a cover, without having to resort to the employment of auxiliary parts or tools for securing the cover to the base, or for removing the cover from the base.

My invention also comprehends forming the ends of the U-shaped metallic member and mounting parts upon said ends, so as to cause them to serve as binding posts having particular advantages.

Reference is to be had to the accompanying drawings forming a part of this specification, in which similar characters of reference indicate corresponding parts in all the figures.

Figure 1 is a vertical section on the line 1-1 of Fig. 2, showing my insulator com-

plete; Fig. 2 is a section on the line 2-2 of Fig. 1, and Fig. 3 is a perspective showing the base and parts immediately associated with it.

A base 4 having generally the form of a disk is provided with a reduced portion 5 extending to a shoulder 6 and provided externally with a thread 7. The base 4 is provided with slots 8 which extend inward and are provided with upwardly extending portions 9 which reach to the top of the reduced portion 5, as will be understood from Fig. 3. A cap 10 is provided with a thickened portion 11, the latter being bounded by a shoulder 12. This shoulder also forms a boundary for a thread 13 which is disposed internally of the cap and fits the thread 7 of the base. Both the base and the cap are made of insulating material.

A longitudinal metallic rod-like member 14 is bent substantially into U-shape, as indicated in Fig. 1, and has its middle portion embedded within the base 4, so as to leave the upwardly extending portions 15, 16 projecting above the base. The portion 15 is threaded. The portion 16 is first provided with a sink 17 as shown in Fig. 3, and is then spun so as to form a mushroom head 17^a, as indicated in Fig. 1. Before spinning the mushroom head 17^a, a flat washer 18, a spring 19 and a couple of concavo-convex washers 20, 21 are slipped over the portion 16. This being done and the head 17^a being spun, the tension of the spring 19 normally forces the washer 18 against the under side of the mushroom head 17^a and also forces the washer 20 down toward the washer 21 and forces the latter against the base.

A wire 22 is inserted through the slot 3 and is brought into engagement with the washers 20, 21 being forced between the two, as indicated in Fig. 1. Mounted upon the threaded portion 15 are nuts 23, 24, and below these nuts and encircling the portion 15 is a metallic washer 25. A wire 26 engages this metallic washer and is held thereagainst by pressure of the nut 23. The nut 24 is merely a nut lock for holding the nut 23 rigidly in position when once adjusted upon the wire.

There are two of the U-shaped metallic members, and I find it convenient to dispose the threaded portion 15 of one opposite the smooth portion 16 of the other, as will be understood from Fig. 3. This gives the

advantage that if the operator desires to secure a wire 22 or 26 to a spring connection, he can readily do so, or he may connect the same wire or another one upon the same side to a binding post containing the threaded portion 15. When a wire is to be connected quickly, it may be simply forced between the washers 20, 21. Where, however, it is desired that the wire when connected shall have considerable pressure upon it, it is preferable to use the nuts 23, 24. By having the two U-shaped members so disposed that one is reversed relatively to the other—that is, the threaded portion 15 of one U-shaped member is adjacent the smooth portion 16 of the other U-shaped member, the operator can use his judgment as to whether a particular wire shall be quickly connected under light pressure or slowly connected under heavy pressure. A screw hole 27 is used for securing the base to a table or a wall.

Though I have illustrated the U-shaped metallic members as comprising round rods of continuous cross-section, it should be pointed out that these rods may have any desired cross-section wherein sharp angles are eliminated, for it is a well known fact that sharp angles and corners, when embedded in a fickle material, tend to create cracks radiating from such corners. The bends of the rods are gradual, also for the purpose of eliminating sharp corners. The member thus formed is of considerable strength and any one of the upstanding portions, above the upper surface of the base 4, is reinforced by a substantial metallic connection with at least one other upstanding portion. It should also be pointed out that the tortuous path provided by the slots 8-9, closed in by the pendent threaded portion of the cap or cover, provides a means for positively preventing withdrawal of the bent wire 26 in case the inner end of said bent wire becomes accidentally disengaged from the binding posts. The wire, however, is readily removable through the open slot, when the cap or cover is removed.

The operation of my device is as follows: The cap 10 being removed, the wires 22, 26, or either of them, are connected as desired, and the cap 10 is then replaced. The shoulder 12, by fitting neatly down upon the outer edge of the reduced portion 5, makes a joint of a kind which can not readily leak or admit moisture or dust. The lower edge of the thickened portion 11, by pressing downwardly against the shoulder 6, makes another joint, both of these joints being held tight by aid of the screw threads connecting the base and the cap together.

With the cap or cover removed, the grooves 8-9 stand open and the binding posts are exposed, so that the operator may readily connect the wires directly to the

binding posts and replace the cover, all without the necessity for threading the wires through holes of any description, and yet, with the cover attached, the wires are positively held by the cover against accidental withdrawal. In connection with the binding posts comprising the spring pressed washers 20-21, it should be noted that the quick attachment and release feature afforded by this construction, is peculiarly adapted to co-operate with the open grooves to the end that, upon removal of the cover, the operator may almost instantly arrange a wire terminal in the groove with its end between the washers, and replace the cap to hold the wire against accidental removal. To remove the wire, he has practically only to detach the cover and lift the wire out, there being no screws or nuts holding the wire, and no holes through which it must be drawn.

Various purposes may be served by aid of the device above described. It may be used, for instance, for dead ending telephone wires, thereby keeping them where they are readily accessible and where they are not apt to do any harm even if, in case of accident, they should become unduly energized by some vagrant wire. Again, by connecting two wires together, say the wire 22 with its mating wire 26, the connection is readily made through one or both of the U-shaped members. One wire can be connected, say by aid of the nuts 23, 24, and may remain thus connected indefinitely, and at any time in order to connect this wire with another wire the latter is simply brought through the slot 8 and into engagement with the washers 20, 21, the spring pressure forcing these washers against the wire last mentioned.

For convenience, I show merely one form of my invention, but it will be understood that I do not limit myself to the exact form nor to the number or details of any or all of the parts above shown and described, nor do I limit myself to any particular combination of the parts, neither do I limit myself to the use of any prescribed materials.

Having thus described my invention, I claim as new and desire to secure by Letters Patent:

1. An insulator, comprising a base of insulating material, a plurality of substantially U-shaped members of conducting material partially embedded therein, each of said U-shaped members having a smooth portion and a threaded portion extending from said base, the threaded portion of one of said U-shaped members being adjacent to the smooth portion of another of said U-shaped members, and mechanism co-acting with said smooth portion and with said threaded portion for facilitating the connection of conductors therewith.

2. In a device of the class described, the combination with a base member carrying a binding post comprising a quick release means for retaining a terminal, of a cover for said base member detachably connected therewith inclosing said binding post and adapted to coöperate with means formed in said base member so as to provide an auxiliary retainer for the terminal whereby to facilitate removal of said terminal from said quick release binding post upon detachment of said cover.

3. An insulator comprising a base member of molded fragile insulating material, an integrally formed U-shaped rod of conducting material having its intermediate portion molded within the fragile material of the base member and having its opposite end portions projecting from the base member, the embedded portion of the rod being of such shape as to present no sharp corners which would tend to fracture the fragile material in which it is molded and said embedded portion serving to hold the opposite projecting end portions rigid in the base member, and said opposite projecting end portions being provided with adjustable means adapting them to serve as binding posts to which conductor wires may be attached.

4. In a device of the class described, the combination with a base member carrying a binding post for retaining a terminal, of a cover for said base member detachably connected therewith inclosing said binding post and adapted to coöperate with means formed in said base member so as to provide an auxiliary retainer for the terminal, whereby to facilitate removal of the terminal from said binding post upon detachment of said cover.

5. In a device of the class described, the combination comprising a base, a binding post projecting from the upper surface of said base; a flange formed upon said base projecting laterally therefrom at a point spaced somewhat below the upper surface thereof for forming, with the side of said base, an angular recess on said base; a cover for said base having an angular portion

adapted to be received in said angular recess and to engage the walls thereof; and the walls of said recess being formed with a groove extending transversely thereof and opening throughout its length into said recess and being closed by the angular portion of said cover, a portion of said cover extending below the upper surface of said base and said groove comprising a tortuous passage directly beneath the lower part of said cover and to the upper surface of said base adapted to receive a bent wire for attaching to said binding post and adapted to hold said wire against accidental withdrawal only so long as said cover is applied, and said binding post comprising quick release means for the end of the wire; all whereby the wire is instantly removable from connection with said binding post and laterally out of said groove upon detachment of said cover.

6. In a device of the class described, the combination with a base member carrying a binding post comprising a quick release means for retaining a terminal, of a detachable member adapted to coöperate when attached with means formed on said base member to provide a tortuous passage adapted to serve as a retainer for the terminal, whereby to facilitate removal of said terminal from said quick release binding post upon detachment of said detachable member.

7. An insulator comprising a base member of molded insulating material, an integral U-shaped rod of conducting material having the end portions of its legs protruding from the surface of said base adapted to serve as binding posts, and the intermediate connecting portion of the U-shaped rod being embedded within the molded material and rigidly connecting the legs.

In testimony whereof I have signed my name to this specification in the presence of two subscribing witnesses.

LOUIS STEINBERGER.
